UNITED STATES PATENT OFFICE.

PETER McILROY, OF ALLISON PARK, PENNSYLVANIA, ASSIGNOR TO ENAMELED METALS COMPANY, OF SHARPSBURG, PENNSYLVANIA, A CORPORATION OF PENNSYLVANIA.

PIPE-PROTECTOR.

1,296,678.

Specification of Letters Patent. Patented Mar. 11, 1919.

No Drawing. Application filed January 23, 1915, Serial No. 3,876. Renewed July 25, 1918. Serial No. 246,783.

To all whom it may concern:

Be it known that I, PETER McILROY, a citizen of the United States, and a resident of Allison Park, in the county of Allegheny and State of Pennsylvania, have invented a new and useful Improvement in Pipe-Protectors; and I do hereby declare the following to be a full, clear, and exact description thereof.

10 My present invention relates to a new and useful method or process for treating pipe or conduit unit protectors of the type described in my Patent No. 1,120,731.

The protector disclosed in this patent consists essentially in a sleeve which is of fragile material and is applied to the pipe or conduit unit either externally or internally thereof to prevent the threads from being heavily coated with enamel. During the 20 coating process some of the enamel seeps in between the protector and the threads of the pipe, and while the protector as originally made was of absorbent material and absorbed the greater part of the enamel, it was 25 found that there was a tendency of the protector to stick to the pipe because of the adhesive properties of the enamel.

The principal object of my present invention is therefore to provide a protector sleeve 30 in which all liability of the protector sticking or adhering to the pipe or conduit unit will be eliminated.

In accordance with my present invention the protectors which are preferably formed of paper (although any other absorbent material may be substituted) are dipped in a bath consisting of a saturated solution of rosin, and this solution of rosin is produced by mixing powdered or granulated rosin 35 with benzin, sufficient benzin being used to make the mixture relatively thin, so that it will have substantially the same consistency as ordinary shellac. (It would of course be possible to produce the liquid bath 40 of rosin by merely melting, over a flame, a quantity of powdered rosin. When rosin is so melted however the resultant product is a sticky, stringy, mass which could not be expediently employed in this process.) 45 It is desirable in the present invention that the rosin solution be thin enough so that the protector will be sufficiently impreg-

nated with the solution by merely being dipped therein. It is also advantageous to employ benzin when reducing the rosin to 55 liquid form since the benzin evaporates after the protector has been allowed to set for a while after the dipping, so that when the benzin has gone off in vapor the protector is in reality impregnated with rosin. 60

It has been found in practice that when the protector has been treated by the process above described it will readily absorb all but a very small portion of the enamel entering between the protector and the pipe 65 during the coating operation, while the protector will not adhere to the threads of the pipe as the rosin appears to be insensible to the adhesive properties of the slight amount of enamel which remains in the 70 threads of the pipe. In this latter connection it may be well to explain that the amount of enamel which is not absorbed by the protector and is allowed to remain in the threads is only sufficient to make an 75 extremely thin coating on the threads and sufficient to keep the same clean during installation.

What I claim is:

1. A thread protector for conduits consisting of a tube formed of relatively stiff absorbent material, the material of said tube being impregnated with rosin. 80

2. The combination with a conduit having a threaded end, of a protector for said threaded end, comprising a tube for covering the threads of said end, said tube being formed of relatively stiff absorbent material, the material of said tube being impregnated with rosin. 85

3. The combination with a conduit having a threaded end, of a protector for said threaded end, comprising a tube for covering the threads of said end, said tube being formed of relatively stiff absorbent material, the material of said tube being impregnated with an indurating material. 95

In testimony whereof, I the said PETER McILROY have hereunto set my hand.

PETER McILROY.
